United States Patent Office.

ALBERT BRUMMEL, OF INDIANAPOLIS, INDIANA.

Design No. 4,391, dated October 11, 1870.

DESIGN FOR AN ADVERTISING-DESK.

The Schedule referred to in these Letters Patent and making part of the same

I, ALBERT BRUMMEL, of Indianapolis, county of Marion and State of Indiana, have invented and produced a new and original Design for Advertising-Desks, of which the following is a specification.

My invention is designed as an advertising medium to be placed in the offices of hotels and other public places.

The construction of my said desk will be fully understood from the accompanying lithographic illustration.

It rests upon four carved legs, as represented in the illustration. At the back of the desk proper is raised a large space, for the purpose of inserting business cards, which is surrounded and divided by a tasty molding, as represented. At the top are three spaces for cards, also surrounded by molding. Below the

middle and larger of the three top spaces is placed an eight-day clock, and on each side of the clock, and below it, are other spaces for advertising-cards; all as represented in the illustration.

The desk proper, to be used for writing purposes, is of the usual form.

What I claim as my design, and desire to secure by Letters Patent, is—

The peculiar form and construction of the advertising-desk herein shown and described.

Witness my hand this 8th day of September, 1870.

ALBERT BRUMMEL.
